(57) CLAIM

The ornamental design for the ice shaver and dispensing system, as shown and described.

DESCRIPTION

FIG. 1 is a front perspective view of the ice shaver and dispensing system;

FIG. 2 is a front side view thereof;

FIG. 3 is a right side view thereof;

FIG. 4 is a rear side view thereof;

FIG. 5 is a left side view thereof; and,

FIG. 6 is a top view thereof.

The portion shown in dashed lines is shown for illustrative purposes only and forms no part of the claimed design.
